UNITED STATES PATENT OFFICE.

GEORGE HENRY MORGAN, JR., AND JOSEPH SALVITTI, OF ELLSWORTH, PENNSYLVANIA.

RAIL-FASTENING DEVICE.

1,148,852.

Specification of Letters Patent. Patented Aug. 3, 1915.

Application filed January 27, 1914. Serial No. 814,724.

To all whom it may concern:

Be it known that we, GEORGE HENRY MORGAN, Jr., and JOSEPH SALVITTI, citizens of the United States, residing at Ellsworth, in 5 the county of Washington and State of Pennsylvania, have invented certain new and useful Improvements in Rail-Fastening Devices, of which the following is a specification.

10 This invention relates to an improved railway rail fastening device.

It is the primary object of the present invention to provide means for fastening railway rails to metal cross-ties; to afford means 15 whereby the danger of rails spreading will be substantially eliminated; to afford means whereby the rails may be removed and replaced in a minimum of time and with absolute precision; and affording means 20 whereby the expansion and the contraction of the rails will not be retarded in any particular.

The above and additional objects are accomplished by such means as are illustrated 25 in their preferred embodiment in the accompanying drawings, described in the following specification and then more particularly pointed out in the claims which are appended hereto and form a part of this 30 application.

In describing our invention in detail reference will be had to the accompanying drawings wherein like characters denote like or corresponding parts throughout the several views, and in which:—

Figure 1 is a side elevation of a railway rail fastening device constructed in accordance with the present invention; Fig. 2 is a top plan view of the device as illustrated 40 in Fig. 1; Fig. 3 is an enlarged end view; Fig. 4 is an enlarged section on the line 4—4 of Fig. 2; and Fig. 5 is a detail perspective view of one of the rail fastening members.

Before proceeding with the description of 45 the drawings, we desire to call particular attention to the fact that while we have evolved our invention with particular reference to its application in connection with metal cross-ties, the same may be readily 50 utilized as a rail fastening device in connection with composition, wood or other ties of varying construction.

Referring now to the drawings by numerals, 1 designates as an entirety, a substan-

tially rectangular hollow metallic tie, pref- 55 erably of an inverted U-shape, whereby the material used is reduced to the minimum. The rails 2 extend transversely of the tie 1, resting thereupon in the usual manner.

A pair of stationary fastening members 60 3 are riveted, bolted or otherwise permanently fastened to the tie 1 as indicated at 4, one of the said stationary rail fastening devices being provided for the respective rails of the railway track, the said rails being 65 thus properly gaged or spaced apart previous to the laying of the ties, thereby eliminating the necessity of subsequent gaging of the railway rails.

A flange 5 is formed integrally with each 70 rail fastening member 3, said flanges being disposed to overlap the inner or adjacent flanges of the base of the rails 2, the said rails being forced beneath the said flanges until firmly engaged thereby, thus insuring 75 proper positioning of the rails.

Disposed to overlap the remote or outer edges of the rail base is an integrally formed flange 6, of an adjustable rail fastening member 7, one of the said members 7 being 80 provided for each rail. The said members 7 are substantially rectangular in form or, by necessity, shaped to embrace the cross-ties 1 in connection with which they are used. Projecting or extending inwardly 85 from each member 7 is a horizontally-flat base plate 8, the inner extremities of the respective plates of the said adjustable members being disposed in close proximity as is clearly illustrated in Fig. 1 of the drawings, 90

to effect, what might be termed, a combination brace, as the said plate members, being integral with the fastening members 7 support and brace the tie 1 throughout the greater portion of its length as well as support and brace said members 7 against movement independent of the tie. After being forced into engagement with the remote base flanges of the railway rails 2, the adjustable fastening members 7 are locked against longitudinal movement upon the cross ties 1 through the medium of a fastening element 9 in the nature of a cotter-pin disposed to extend transversely of the said cross tie to provide an abutment for the said members 7. 100 105

From the above, taken in connection with the accompanying drawings it is apparent that the labor attendant upon the fasten-

ing and unfastening of the railway rails upon the cross ties is reduced to the minimum. In assembling the device, the rails 2 are first forced beneath the stationary fastening members 3, said rails being thus properly positioned or gaged. The rail fastening members 7 are then slipped over the respective extremities of the tie 1 until the flanges 6 thereof overlap the opposite flange 10 of the rail base from that engaged by the flange 5 of the stationary member 3. When positioned as above, it is apparent that by inserting the fastening element 9 in the openings provided therefor, longitudinal movement of the adjustable or movable rail fastening members 7 is prevented, while lateral or vertical movement of the members is rendered impossible by reason of the peculiar formation thereof. It is to be understood that the shape of the adjustable rail fastening members 7 must necessarily be varied to correspond with the shape, in cross section, of the cross-ties 1 in connection with which they are used.

In reduction to practice, we have found that the form of our invention, illustrated in the drawings and referred to in the above description, as the preferred embodiment, is the most efficient and practical; yet realizing that the conditions concurrent with the adoption of our device will necessarily vary, we desire to emphasize the fact that various minor changes in details of construction, proportion and arrangement of parts may be resorted to, when required, without sacrificing any of the advantages of our invention, as defined in the appended claims.

Having thus fully described our inven-

tion, what we claim as new and desire to secure by Letters Patent, is:—

1. A rail fastening means consisting of a base plate adapted to be arranged beneath the cross-tie, a sleeve like enlargement formed at one end of the base plate, the cross-tie extending therethrough, and means integral with the said enlargement and engageable with the railway rail, to serve as a retaining means therefor.

2. A device for fastening railway rails to cross-ties including a stationary member adapted for engagement with one of the base flanges of the rail, an adjustable rail fastening member, a plate-like extension integral with the said adjustable member, said extension being disposed for engagement with the under face of the tie, said fastening member being shaped to conform with the shape of the tie in cross section and to embrace the said tie to prevent lateral and vertical movement of said member independent thereof, a flange integral with said member, said flange being adapted for engagement with the opposite rail base flange from that engaged by said stationary member, and means extending transversely of the tie to provide an abutment for said adjustable member to lock said member against longitudinal movement upon said tie, as and for the purpose set forth.

In testimony whereof we affix our signatures in presence of two witnesses.

GEORGE HENRY MORGAN, Jr.
JOSEPH SALVITTI.
